WAISTBAND FOR GARMENTS

Filed Dec. 12, 1949

INVENTOR.
BY SAMUEL E. AXLER

ATTORNEY

Filed in the Patent Office October 10, 1949. Serial No. 132,511. This application is a continuation-in-part of my application, Serial No. 100,330, filed January 10, 1946, now abandoned.

UNITED STATES PATENT OFFICE

2,525,060

WAISTBAND FOR GARMENTS

Samuel E. Axler, Denver, Colo.

Application December 12, 1949, Serial No. 132,511

2 Claims. (Cl. 2—221)

1 This invention relates to a waistband construction for skirts and similar garments, and has for its principal object the provision of a waistband which may expand to accommodate waists of larger sizes and to provide a snug-fitting waistband at all times.

Another object of the invention is to provide an expandible waistband in which the expandible features and the degree of expansion of the band will be entirely concealed.

A further object is to provide a skirt construction in which a single piece of material will act to form a pocket, a tunnel belt loop, and a covering for the elastic or expandible portions of the waistband.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a front view of the upper portion of a skirt, with the improved waistband construction incorporated therein;

Fig. 2 is a rear view of the upper portion of the skirt of Fig. 1, illustrating the rear flaps of the skirt opened to expose the inner face of the expandible portion of the waistband;

Fig. 3 is an enlarged, fragmentary, inside view of a portion of the improved waistband construction, with a concealing tab released and lifted to expose the elastic or expanding material; and

Fig. 4 is a similar outside view with the concealing tab released and turned back to expose the expanding portion.

In the drawing, the upper portion of a skirt is illustrated having a front panel 10 stitched to side panels 11 by means of vertical seams 12. The front panel 10 extends upwardly to the top of the waist of the skirt, thence is folded inwardly and downwardly to form an inside depending flap or fold 13. The side panels 11 terminate in waistband members 14 which are joined at the back of the skirt by means of any suitable fastening device, such as a button 15 and buttonhole 16. The side panels may be joined at the back of the skirt in any desired manner, such as by means of a vertical seam 20 and a slide fastener 21.

The waistband members 14 each terminate in

2 an elastic member 17 having a width substantially equal to the width of the waistband member 14. The inside edges of the elastic members 17 are secured to the opposite sides of the front panel 10 by means of the stitching of the seams 12.

Therefore, when the skirt is in place, the elastic portions 17 will maintain the front panel 10 tight and smooth across the front of the skirt; will accommodate all flexions of the wearer; and will maintain the waistband tight and smooth at all times. There is sufficient stretch or elasticity in the elastic members 17 to allow the waistband to expand sufficiently to accommodate several sizes larger than the normal size of the skirt.

The material of the side panels 11 is cut with excess width. This excess width is taken up in gathers 18 which are pleated over each other and 20 stitched to the lower edge of the elastic members 17, as indicated at 19, Fig. 5. This provides sufficient excess material in the side panels to accommodate the maximum expansion of the elastic members 17.

25 The above-described expandible or elastic waistband construction would not present a sufficient ornamental appearance, due to the exposure of the gathers or tucks 18 and the elastic members 17. In this improved skirt construction, however, all of the gathers, tucks, and elastic members are entirely and attractively concealed, regardless of the degree of expansion or contraction. This is accomplished by stitching two patch pockets 22 on the front of the skirt over the side panels 11 and slightly overlapping each side of the front panel 10 by means of U-shaped lines of stitching 21.

30 The pockets 22 terminate at their tops in relatively long flaps which extend upwardly over the waist portion of the skirt to form open tunnel belt loops 23. The flaps are then folded inwardly and downwardly over the inside of the waist portion to form concealing tabs 24. The concealing tabs 24 are secured by a single point of stitching 25. This single point of stitching attaches the tab 24 at only one point and at approximately the middle of the elastic member 17 so that when the latter is stretched, the stitching is not interfered with, and the flaps 24 will be maintained accurately centered over the elastic member at all times.

The flap portions 23 and 24 are relatively narrower than the pockets 22 so as to provide a cut-back hand entrance 26 at each side to the pockets. The stitching 27 at the outer sides of the pockets

terminates well below the waist portion. This accomplishes two purposes, first, it allows ample space for the hand opening 26, and it prevents interference with the sideward movement of the upper portion of the panels 11 relative to the center panel 10.

It will be noted that the improved waistband stays tight and snug about the user's waist at all times so as to maintain tight, snug engagement with the skirt of the user's blouse to prevent the latter from pulling away from the skirt.

While a specific form of the improvement has been described and illustrated herein, it is to be understood that the same may be varied; within the scope of the appended claims, without departing from the spirit of the invention.

Having thus described the invention, what is claimed and desired secured by Letters Patent is:

1. A waist construction for garments comprising: a front center garment panel terminating at the waist of the garment; an elastic member secured to each side of the upper extremity of said front panel; a waistband secured to each elastic member and extending around the sides and back of the waist; gathers in the garment terminating at and secured to said elastic members; and a concealing member secured to the front of the garment below said elastic members and extending upwardly over the front portion of the latter, thence extending downwardly over the rear thereof, the downwardly extending portions being secured to said elastic members at a single point adjacent the middle of the latter, the lower front portions of said concealing members being secured to the front of the garment by sub-

stantially U-shaped stitching to form a patch pocket on said garment.

2. A waist construction for garments comprising: a front center garment panel terminating at the waist of the garment; an elastic member secured to each side of the upper extremity of said front panel; a waistband secured to each elastic member and extending around the sides and back of the waist; gathers in the garment terminating at and secured to said elastic members; patch pockets, stitching securing each patch pocket to the front of the garment below one of said elastic members, said stitching terminating below the elastic member; a tunnel belt loop extending upwardly from each patch pocket over the forward face of one of said elastic portions and over the forward faces of the gathers secured to said elastic member; and a concealing flap extending from each tunnel belt loop inwardly and downwardly over the inner face of each elastic portion and its associated gathers.
